VALVE MECHANISM FOR MOTORS OF
PUMPS

Frank David Butler, United States Navy

Application January 21, 1938, Serial No. 186,250

5 Claims. (CL. 121—157)

(Granted under the act of March 3, 1883, as
amended April 30, 1928; 370 O. G. 757)

While my present invention relates particularly to valve operating mechanism for motors of reciprocating pump wherein an expansive fluid is used for the actuating medium of such motor and the actuating means of the main valve of such motor and wherein the actuation of said main valve is controlled by pilot valve, it also relates to valve mechanisms wherein the main valve of the motor is operated direct by some moving element of such motor. In such motors, I have found that, due principally to poor design, a considerable quantity of the expansive fluid actuating medium is wasted during each movement of the main valve and each stroke of the main piston member thereof, that the assemblies of the main and pilot valve members of such motors are not very compact in construction and that in general these valve mechanisms are expensive to build and are inefficient, unreliable and not very durable in operation.

The solution of these major problems, in addition to the complete accomplishment of their many minor resulting problems, has been long and vainly sought by many in this art.

The major concept of my present invention is the complete solution of these problems and by the provision of a simple, durable, efficient and relatively inexpensive valve assembly means for its practical and commercial accomplishment.

More specific concepts of my invention contemplate the following:

The provision of an annular shaped main valve member slidably mounted within a cylindrical bore of a suitable valve chest located adjoining the cylinder of the motor, a pair of cylindrically shaped fluid actuating chambers for the purpose of alternately containing the expansive fluid for actuating the main valve member, one chamber being located adjoining each end of the main valve member and both chambers being considerably smaller in diameter than the outer diameter of the main valve member.

The provision of a cylindrically shaped pilot valve member slidably mounted within the main valve member and suitable expansive fluid control ports located therein for the purpose of controlling the expansive actuating fluid admittance to and exhaust from the actuating chambers whereby the movement of the pilot valve member may control the actuation of the main valve member.

The provision of cushioning means for the main valve member whereby either the main or the pilot valve or both may close off the exhaust release from said actuating chambers as the

main valve member nears the end of its exhaust cycle stroke in either direction of travel thus forming dash-pot compression spaces within the actuating chambers and cushioning the main valve as it nears the ends of its strokes.

The provision of means for producing greater efficiency in valve mechanisms of this type by relatively reducing the cubical capacity of the main valve actuating chambers by reducing the diameters of these chambers considerably below the diameter of the main valve member, which latter diameter is the usual size of the usual main valve actuating chambers, and also by reducing the cubical capacity of the main cylinder ports by lengthening out the main valve member and locating the enlarged port control portions of this valve relatively close to the ends of the motor cylinder, this reducing excess waste of the expansive fluid actuating medium;

The provision of compact means for operating the pilot valve member and,

The provision of means comprising new and useful entities which practically, commercially, efficiently and economically practice to be most advantageous in each of the foregoing, and such other respects which will more clearly appear and be understood by those skilled in this art, from the accompanying drawings and the following description, and the appended claims:

It will be readily appreciated by those skilled in this art, after understanding my invention, that various changes may be made in the means disclosed herein which will produce the same results in substantially the same manner without digressing substantially from my inventive concept or sacrificing any of its outstanding inherent advantages.

With reference to the drawings:

Fig. 1 is a vertical section through the embodiment of my pilot controlled, fluid actuated valve mechanism as applied to the usual type of pump motor cylinder.

Fig. 2 is a vertical section at right angles to the section illustrated in Fig. 1 and shows a preferred but modified embodiment of the valve mechanism including compact actuating means for the pilot valve thereof.

Fig. 3 is similar to Fig. 2 in section illustrating a second modification of the valve mechanism.

Fig. 4 is a side elevation of the usual type vertical, reciprocating, double acting pump assembly with motor attached and diagrammatically illustrates the usual means for mechanically operating the pilot valve member.

Fig. 5 is a plan view in section of a portion of Fig. 3 on line 5—5 of Fig. 3.

Fig. 6 is an enlarged detail section of a portion of the valve mechanism assembly illustrated in Fig. 1, and diagrammatically illustrates the movement of the pilot and main valve members from one end of their stroke travel to the opposite end; and

Fig. 7 is an enlarged detailed section of a portion of the modified valve mechanism assembly illustrated in Fig. 3 and diagrammatically illustrates the movement of the pilot and main valve members from one end of their stroke travel to the opposite end.

In the drawings, in which the same reference characters indicate the same parts in the several views, Fig. 4 illustrates the usual type of vertical, double acting, reciprocating pump assembly having a motor cylinder 1 opposed by a pump cylinder 2, a piston rod 3 connecting the motor piston 4 and pump piston or plunger 5; a cross-head member 6 secured to said piston rod approximately midway between said pistons to actuate the mechanism which operates the pilot valve; a suitably mounted oscillating arm member 7 adapted to be actuated by the cross-head member; a suitably mounted, hollow, trunnion bearing supported tappet member 8 supported in and actuated by the oscillating arm member 7; a tappet rod member 9 to extend through the hollow portion of tappet member 8 and having secured thereto, adjoining either end of the member 8, suitable adjustable tappet nut assemblies 10 and 10a which are adapted to be intermittently and alternately contacted by the adjoining ends of the tappet member 8 to transmit the reciprocating motion received from said tappet member, via the tappet rod member 9 to the stem end 11a of the pilot valve member; and a forked crosshead member 12 secured to the stem end 11a and coupling the tappet rod member 9 and the stem of the pilot valve member together by a suitably mounted wrist pin 12a, thereby allowing rod 9 sufficient swing for alignment with the stem end 11a of the pilot valve member.

With reference to Figs. 2, 3 and 5, the motor power piston 4 is suitably mounted for reciprocation within the motor cylinder 1 in the usual manner by expansive fluid supplied thereto and exhausted therefrom through a suitable valve chest 13. This chest 13 has a bore 13a preferably in a plane parallel to closely adjoining the bore 1a of the motor cylinder 1. Suitable cylinder and valve chest communication ports 14 and 14b, having the relatively small exhaust cushioning ports 14a and 14c respectively forming a part thereof, extend at right angles to the bores 1a and 13a to connect respectively the upper end of the cylinder bore 1a with the upper end of the valve chest bore 13a and the lower end of the cylinder bore 1a with the lower end of the valve chest bore 13a. A suitable expansive fluid supply connection 15 and exhaust connection 16 are in constant communication with the bore 13a of the valve chest 13.

In the motor drive for the pump assembly as described in the previous paragraph, I provide the combination of main and pilot valve assembly illustrated in Figs. 1 and 6 with the modifications illustrated in Figs. 2, 3, 5 and 7 for the purpose of controlling the expansive fluid supply from the supply connection 15 to the bore 1a of the cylinder 1 and the expansive fluid exhaust from the bore 1a of the cylinder 1 to the exhaust connection 16. In all the assemblies the pilot

valve members are located within the main valve members and are operated by an external mechanical or other appropriate means to control intermittently and alternately the expansive fluid supply from the normal source of supply 5 to the expansive fluid actuating chambers, which form the motor cylinders for the actuation of the main valve members, and the expansive fluid exhaust from said expansive fluid actuating chambers to the normal exhaust exit connection. 10

In each of these valve assemblies the main valve member 17 consists of a hollow, elongated spool shaped metal casting which is cored out, constructed and machined so as to reduce its weight to a minimum appropriate to its size, 15 length and required strength. Upper and lower piston head portions 17a and 17b respectively are located on valve member 17 the same distance apart from one another as the cylinder and valve chest communication ports 14 and 14b. 20 Suitable relatively wide snap type upper and lower pressure seal rings 18 and 18b have internal tongue portions which fit in external grooves in the upper and lower head portions 17a and 17b respectively. Removable upper and lower bushings or liners 19 and 19b are press fitted to the chamber bore 13a and are secured in position therein by the dowel screws 20. Machined in the circumferences of these bushings are the equally spaced ports 19a and 19c which coincide with and 25 form an extension of the ports 14 and 14b respectively. The ports 19a and 19c are relatively narrower in width than the main valve snap type pressure seal rings 18 and 18b respectively. These seal rings slidably fit in the inner bores 30 19d and 19e respectively of liners 19 and 19b to open and close the ports 19a and 19c, as will be described more specifically later.

With reference to Figs. 1 and 6, only the rings 18 and 18b contact the walls of the bores 19d and 19e. The main valve proper is internally supported in the bores of the chest and liner and slidably mounted on upper and lower bores 17c and 17d cooperating with inward extending projections 21a and 21c of upper and lower bore 45 covers 21 and 21b respectively of the valve chest 13. The length of the projections 21a and 21c between their inner ends and valve stop shoulders 21d and 21e is a trifle less than the depth of their respective cylinder chamber bores 17c and 17d so 50 that the outer end faces 17e and 17f of the main chamber 17 will contact the shoulders 21d and 21e respectively and prevent the inner end faces of the bores 17c and 17d from contacting with the inner end faces of projections 21a and 21c. 55

The stem 11a of the pilot valve member 11 extends throughout the length of the valve chest 13 and is preferably manufactured of some rust resisting steel alloy. This stem should ordinarily form the pilot valve member proper as illustrated in Figs. 2, 3, 5 and 7, or it may, as in this instance, have pressed thereover and secured thereto an upper cast iron sleeve 11c and a lower cast iron sleeve 11d to form the pilot valve member 11 and slidably fit within the inner bore 17g of the main valve member 17 and inner bores 21f and 21g located at the inner ends of the projections 21a and 21c. Suitably cylindrically shaped recesses 21h and 21i are bored in the outer ends of the valve chest bore covers 21 and 21b to form upper and lower stuffing or packing boxes 21h and 21i respectively for the valve stem 11a. These boxes contain the throat bushings 22, packing 22a and glands 22b. The glands 22b 75

are adjustably secured by the stud bolts 22c threaded into the covers 21 and 21b.

The pilot valve member 11 has two diagonal ports extending therethrough. The upper diagonal port 11e originates at its lower end in an annular shaped groove 11g located in the outer circumference of the pilot valve member 11. The lower diagonal port 11f originates at its upper end in a similar annular shaped groove 11h likewise located in the outer circumference of the pilot valve member 11. External to the outer diameter of the pilot valve member 11 and internal to the bores 17c and 17d, of the main valve structure intermediate the inner ends of these bores and the inner ends of the projections 21a and 21c respectively are formed two annular shaped chambers 17h and 17i respectively for the operation of the main valve member 17.

Adjoining the outer ends of the previously mentioned inner bores 21g and 21f of the projections 21a and 21c respectively, and external to the outer diameter of the pilot valve member 11 are two annularly shaped exhaust passageway recesses 16b and 16c respectively. These recesses 16b and 16c communicate through ports 16d and 16e respectively located in their outer circumferences with the exhaust communication passageway 16a. Passageway 16a is a cored connection from the bore 13a of the valve chest to the exhaust outlet exit connection 16 attached thereto. The valve chest bore covers 21 and 21b are secured to the valve chest 13 by the stud bolts 21j and are accurately centered in the bore 13a of the valve chest by the snug fit of the boss projections 21k thereof in the ends of the bore. The valve chest 13 has two boss projections 13b integral therewith which coincide with two similar boss projections 1b integral with and located adjoining the ends of the body of the main cylinder 1. The valve chest 13 is secured to the cylinder body 1 and held in contact with the boss projections 1b by the stud bolts 13c.

The central portion of the valve chest 13 is cored out and forms the expansive fluid supply chest 15a which affords constant communication between the supply connection 15 and the inner portion of the cavity of the bore 13a. Elongated ports 17j and 17h extend radially through the main valve member 17 from the outer periphery thereof to the inner bore 17g thereof intermediate the bores 17c and 17b. Port 17j is the upper expansive fluid supply port for the upper actuating chamber 17h and port 17k is the lower expansive fluid supply port for the lower actuating chamber 17i for operating the main valve member 17.

In Fig. 1 the main valve 17 and pilot valve 11 are illustrated in their normal full downward travel positions under which condition the other moving elements of the pump assembly should normally be in the positions illustrated in Fig. 4 and the motor piston would normally be in the position illustrated in Fig. 3. Under these conditions the expansive fluid entering the supply chest 15a from the source connection 15 would flow through the radial ports 19c in liner 19b into the lower communication port 14b connecting valve chest bore 13a with cylinder chest bore 1a, thence through the diagonal port 14c to the space below the main motor piston 4. Simultaneously the space within the cylinder bore 1a above the main piston 4 would have free and open access to the exit exhaust connection 16. The expansive fluid would flow and be exhausted from above the piston via the upper communica-

cation port 14, the radial ports 19a into the exhaust communication passageway 16a, and thence into the exit exhaust connection 16.

Simultaneously with the above described expansive fluid supply to and exhaust from the main cylinder, the supply expansive fluid has free access to flow from the supply chest 15a to the upper actuating motor chamber 17h of the main valve 17, via the elongated port 17j, into the diagonal port 11e, or into the annular shaped groove 11g and thence into the diagonal port 11e, and thence into the chamber 17h and holds the main valve 17 in its full downward position of travel with the lower end face 17f in contact with the shoulder 21e of the projection of the lower cover 21b in such a position of travel as to allow full free access passage through ports 19a and 19c. As the piston 4 is forced upward the oscillating arm 7 is oscillated on its pivot point upward, as diagrammatically illustrated in Fig. 20 4, and carried with it the tappet member 8 which latter contacts the nut assembly 10 of the rod 9 and forces the latter and consequently the pilot valve member 11 upward to a full upward travel position. This will place the diagonal ports 11e 25 and 11f and the annular shaped grooves 11g and 11h of said member 11 in the position as diagrammatically illustrated by the dotted lines in Fig. 1 and the full lines in Fig. 6 to cut off the supply of the expansive fluid to the upper actuating chamber 17h and connect to the upper exhaust recess 16b via the upper diagonal port 11e, as illustrated by the dotted lines in the upper portion of Fig. 1.

Simultaneously, as illustrated by the dotted lines in the lower portion of Fig. 1 and as diagrammatically illustrated in detail in Fig. 6, the lower actuating chamber 17i of the main valve member 17 is connected to the expansive fluid supply chest 15a and the supply expansive fluid flows from chest 15a via the lower elongated port 17k in valve 17 into the lower annular shaped groove 11h and the lower diagonal port 11f, and thence into the lower actuating chamber 17i. This forces the main valve member 17, as diagrammatically illustrated in Fig. 6, from its full downward position wherein it contacts the shoulder 21e to its full upward position of travel, only illustrated in part in Fig. 6, in which latter position of travel its upper end face 17e contacts the shoulder 21d, and a full free access passage through the ports 19a and 19c is attained. During the upward travel of the main valve 17 and a predetermined distance of travel before the upper end face 17e thereof contacts the shoulder 21d, the upper edge of the bore 17g thereof adjoining the upper actuating chamber 17h thereof passes upward beyond the upper annular shaped groove 11g and the lower end of the upper diagonal port 11e of the pilot valve member 11 and thus cuts off the exhaust release between chamber 17h and the upper exhaust recess passageway 16b, forming an efficient cushioning dashpot of the chamber 17h which causes a high compression of the expended expansive fluid remaining in said chamber 17h and results in the main valve member 17 coming gently into contact with the upper shoulder 21d, in place of violently, as would otherwise be the case. During this same upward travel of the main valve 17, 70 the upper snap type ring 18 cuts off the exhaust release communication existing between the upper end of the cylinder bore 1a and the exhaust exit connection 16, as previously described, by travelling upward and covering the ports 19a, 75

and opens communication between the expansive fluid supply chest 15a and the communication port 14 leading to the upper end of the cylinder bore 1a by uncovering and passing on above said ports 19a to thus admit the supply expansive fluid from chamber 15a to port 14 and the space in bore 1a above the main piston 4. Simultaneously during this upward travel of the main valve 17, the lower snap type ring 18b cuts off the expansive fluid supply communication existing between the supply chest 15a and the lower end of the cylinder bore 1a, as previously described, by travelling upward and covering the lower ports 19c and opens communication between the lower end of the cylinder bore 1a and the exhaust exit connection 16 by uncovering and passing on above the lower ports 19c to thus release the expanded expansive fluid from beneath the main piston 4 in the cylinder bore 1a via the lower communication ports 14b and lower valve ports 19c into the exhaust passageway connection 16a, and thence into the exhaust exit connection 16.

Immediately following the foregoing functions, the main piston 4 starts travelling downward and as it nears the bottom of its downward travel, and the positions as illustrated in Figs. 1 and 4, the tappet member 8 strikes the tappet nut assembly 18a of the rod 9 and forces the pilot valve member 11 downward to the position illustrated in Fig. 1, whereby the expansive fluid supply from the chamber 15a to the lower actuating chamber 17i, as previously described, is cut off and discontinued and in place thereof, with reference to the full lines of the main valve 17 and the dotted diagrammatic lines representing the pilot valve 11 in Fig. 6, the chamber 17i is connected direct to the lower exhaust recess 16c via the lower diagonal port 11f in the pilot valve 11, and the expansive fluid in the chamber 17i is expanded into the recess 16c. Simultaneously the upper actuating chamber 17h is connected to the expansive fluid supply chest 15a and the expansive fluid flows from supply chest 15a via the upper elongated port 17j into the annular shaped groove 11g and the diagonal port 11e, and thence into said upper actuating chamber 17h whereupon the main valve 17 is forced downward from its uppermost position of travel, as previously described, towards the position of travel in which it is illustrated in Fig. 1. As the valve 17 nears the latter mentioned position of travel, the lower edge of the bore 17g thereof adjoining the lower actuating chamber 17i thereof passes downward beyond the lower annular shaped groove 11h and the upper end of the lower diagonal port 11f to cut off the exhaust release between said chamber 17i and the lower exhaust recess passageway 16c and, similar to that previously described for the upper travel of valve 17, form an efficient cushioning dash-pot of the chamber 17i, which causes a high compression of the remaining expansive fluid in the chamber 17i and results in the main valve member 17 coming gently into contact with the lower shoulder 21e in place of violently, as would otherwise be the case, whereupon the complete cycle of operation just described is repeated.

The capacity of the actuating cylinders 17h and 17i of the main valve member 17 should only be sufficient to insure the proper operation of the valve member, and the clearance spaces between the inward ends of said cylinders and the ends of the projections 21a and 21c respectively acting as piston plungers therein should be as close as possible to reduce to a minimum, waste of the

expansive fluid medium in the type of installation just described, the exhaust expansive fluid only comes in contact with the stuffing box packing 22a and this packing should be maintained sufficiently tight on the stem 11a of the pilot valve member 11 to prevent the latter from moving in an abnormal manner, such as due to the slight drag thereon by the main valve 17.

The valve chest mechanism embodiment just described is identical to that of my preferred embodiment shown in Fig. 2, with the following exceptions: The metal sleeves 11c and 11d of valve member 11 and the shoulders 21d and 21e of the valve chest bore cover projections 21a and 21c are eliminated. The inner end faces of the projections 21a and 21c are machined to a smaller angle than the inner ends of chambers 17h and 17i and provide the travel contact stops for the main valve member 17 without forming major seals between the contact joints of said inner ends respectively, and the usual type of mechanical actuating means of the pilot valve member 11, as previously described, is substituted by my preferred actuating device for such valve member.

The construction and operation of my pilot valve actuating device for the preferred embodiment of my valve assembly shown in Fig. 2 is as follows: In this device the valve 11 is operated by the main piston 4 via the upper and lower poppet valve shaped tappet rods 6a and 6b and the upper and lower oscillating levers 7a and 7b respectively. These rods are slidably mounted in suitable packed guides 23 and 23a which are threaded into the upper and lower cylinder heads 24 and 24a respectively, and form pressure tight access openings through said cylinder heads wherein the rods may operate. The outward side of the enlarged contact discs at the inward ends of the tappet rods 6a and 6b are provided with suitable valve discs 6c and 6d respectively which are adapted to intermittently and alternately contact suitable valve seats 23b and 23c located in the inward ends of the guides 23 and 23a, respectively. This contact depends upon the difference in pressures on either side of the piston 4 in the cylinder bore 1a, the higher pressure tends to seat the tappet rod adjoining it, thus resulting in the packing of guides 23 and 23a being subjected to reduced pressure only.

The upper and lower oscillating levers 7a and 7b are forked at their inward ends and suspended between pairs of heat treated roller pins 25 in upper and lower crossheads 25 and 25a respectively secured to oppositely threaded opposite ends of the valve member 11. Levers 7a and 7b are fulcrumed on the pins 7e and 7f respectively of stanchions 7c and 7d threaded into the cylinder heads. The levers 7a and 7b are provided with suitable heat treated rollers and roller pins 7g and 7h respectively for contact with tappet rods 6a and 6b. The ends of the valve member 11 are provided with the lock nut 25c for adjusting the stroke of the main piston 4 by reducing the distance between the crossheads 25 and 25a and causing the piston 4 to contact the disc ends of the tappet rods 6a and 6b earlier as the piston nears the end of its stroke, thus reversing the pilot valve earlier and resulting in shortening of the stroke of the piston, and vice versa.

In Fig. 2 the moving elements of the pump motor are illustrated in the position they occupy at the completion of the upward stroke of the

piston 4. The piston 4 is in contact with the upper tappet rod 6a, thus mechanically reversing by lifting the pilot valve member 11. This results in automatically reversing by forcing upward main valve member 17 and further results in the expansive fluid being released from below and admitted to above the piston 4 in the bore 1a of cylinder 1. The tappet rod 6a remains in contact with the upper side of the piston until such time as the pressure is higher above than below the piston, whereupon it is forced a slight distance further upward into contact with its seat 23b as the piston starts receding in the bore 1a on its downward stroke. As the piston 4 nears the end of its downward stroke, it contacts the enlarged disc of the lower tappet rod 6b and forces the pilot valve 11 to reverse, as diagrammatically illustrated by the dotted positions of lever 7a and 7b and the diagonal ports 11e and 11f, as shown in Fig. 2.

In the embodiment of my invention illustrated in Figs. 3, 5 and 7, the cylindrical ends of the main valve 17 project into the valve chest bore covers 21 and 21a, instead of the reverse as in the other figures, and support the main valve within the valve chest bore. The upper and lower valve actuating chambers 17h and 17i are formed intermediate the ends of the main valve 17 and the packing boxes 21h and 21i, external to pilot valve member 11 and internal to the covers 21 and 21b respectively. The upper and lower exhaust recesses 16b and 16c and the exhaust ports 16d and 16e thereof are formed in the valve 17 external to valve 11, these ports 16b and 16c in this instance in addition to the diagonal ports 11e and 11f of member 11 cut off the exhaust release before the main valve 17 reaches the ends of its strokes. The upper and lower diagonal ports 11e and 11f respectively alternately and intermittently control the expansive fluid supply to and exhaust from the actuating chambers 17h and 17i of the main valve 17, as in the other embodiments. One disadvantage of this embodiment is the fact that the live expansive fluid would be adjacent the inner ends of the packing boxes 21h and 21i alternately and intermittently during the operation of reversing the main valve. The lower portion of this embodiment is illustrated in detail in Fig. 7, the full lines showing the uppermost travel of the valves 11 and 17 and the dotted lines illustrating diagrammatically the full downward travel of the valves.

The usual type pilot valve actuating means, as illustrated in Fig. 4, is not adaptable to pumps wherein the motor thereof is short coupled to the pump proper, but the type of valve mechanism as described herein and illustrated in Fig. 2 can be used on either long or short coupled pump assemblies.

With reference to Fig. 2 it is obvious that the pilot valve actuating device therein illustrated could be coupled direct to the main valve 17 and would thus actuate this main valve directly, eliminating the use of the pilot valve. All that would be necessary to be done in such case would be to eliminate the diagonal ports 11e and 11f in valve 11, secure valve 17 midway in length on and tightly to 11, the latter thus forming the stem for 17 and also the guide, and eliminate the projections 21a and 21c, or cut them off at the inward ends of the exhaust passageways 16b and 16c respectively. The stroke of the piston 4 could then be adjusted by screwing stem 11 into or out of crossheads 25 and 25a.

The invention described herein may be manufactured and/or used by or for the Government of the United States of America for governmental purposes without the payment of any royalties thereon or therefor.

Having thus set forth and disclosed the nature of this invention, what is claimed is:

1. In an expansive fluid actuated, pilot controlled valve mechanism for a motor cylinder, a valve chest and a valve chest bore, said valve chest adjoining said motor cylinder, an elongated spool shaped expansive fluid actuated main valve controlling the actuating expansive fluid supply to and exhaust from the motor cylinder, a pair of annular shaped chambers, one adjoining each end of said main valve and both being of appreciably smaller outside diameter than the spool portions thereof providing motor cylinders for actuating said main valve, a cylindrical shaped pilot valve slidably mounted centrally within said main valve, said pilot valve having a plurality of valve ports extending diagonally therethrough to intermittently and alternately control the expansive fluid supply to and exhaust from each of said main valve actuating motor cylinders, and cooperative means between said main valve and said valve ports in said pilot valve forming dash-pot cushioning chambers of said main valve motor actuating cylinders to cushion said main valve at the ends of its actuated stroke travel.

2. An expansive fluid actuated, pilot controlled valve mechanism for a motor cylinder and a motor piston comprising an elongated spool shaped expansive fluid actuated main valve, a pilot valve, a valve chest, a valve chest bore, said main valve being slidably mounted in said valve chest bore adjoining the motor cylinder, a pair of annular shaped chambers, one adjoining each end of said main valve, said chambers being of appreciably smaller diameter than the enlarged spool portions of said main valve and constituting motor cylinder means for the actuation of said main valve, a cylindrically shaped pilot valve slidably mounted centrally within said main valve, a pair of ports extending diagonally through said pilot valve, one for each of said annular shaped chambers, intermittently and alternately forming communication between a source of expansive fluid supply and its respective annular shaped chamber and between its respective annular shaped chamber and an exhaust exit, means for externally and intermittently reciprocating said pilot valve whereby such reciprocation of said pilot valve causes said main valve to become expansive fluid actuated to reciprocate intermittently within said valve chest to control the expansive fluid supply to and exhaust from the motor, and means whereby said main valve as it nears the ends of its stroke travel during such actuation cooperates with said diagonal ports in said pilot valve and closes off the exhaust release from said annular shaped chambers to provide dash-pot cushioning means for gently stopping said main valve at the ends of its stroke travel.

3. An expansive fluid actuated, pilot controlled valve mechanism for a motor cylinder comprising a cylindrically shaped expansive fluid actuated main valve, to control the expansive fluid supply to and exhaust from the motor cylinder, a valve chest and valve chest bore adjoining the motor cylinder, said main valve in said valve chest bore, a pair of covers for said valve chest, one closing each end of said chest bore and secured concentrically with said bore, projections extending inwardly from said bore covers providing means

slidably supporting said main valve within said valve chest, a cylindrically shaped pilot valve slidably mounted in and concentric with said main valve and said covers, a plurality of annular shaped chambers external to said pilot valve and internal to the fit between the projections of said covers and said main valve adjoining the inner ends of said covers and the outer ends of said main valve forming actuating motor cylinders wherewith to actuate said main valve, and means external to said valve chest for intermittently reciprocating said pilot valve.

4. Claim 3 characterized by port communication extending radially through the midsection of said main valve and connecting a source of expansive fluid supply with a portion of the midsection of the fit of said main and pilot valves, a pair of ports extending diagonally through said pilot valve, one for each of said annular shaped chambers intermittently and alternately forming communication means between the source of expansive fluid supply and its respective annular shaped chamber and between the latter and an exhaust exit, and cooperative means between said main valve and said ports.

5. Claim 2 characterized by said means for reciprocating said pilot valve consisting of a pair of elongated cylindrical shaped actuating rods, combined cage and packing stuffing box members secured one in each end of the motor cylinder in a plane parallel to the bore of such cylinder, a valve seat portion at the inward end of said box, said actuating rods projecting through said box members into the motor cylinder bore to be intermittently and alternately actuated by the main piston of such motor cylinder, an enlarged disc portion forming a part of each rod at the inward end thereof intermittently seating against the corresponding seat portion of its respective stuffing box member to thus seal such box during such intermittent seating, and a pair of pivoted levers oscillatably mounted one adjoining the outer end of each of said actuating rods, adjustable means on said pilot valve coupling said levers together, whereby said pilot valve may receive an increased parallel motion in relation and proportion to the motion of said actuating rods during the intermittent actuation of the latter by the motor piston.
